UNITED STATES PATENT OFFICE.

CARL G. NYBERG, OF WORCESTER, MASSACHUSETTS.

PUMP.

SPECIFICATION forming part of Letters Patent No. 716,090, dated December 16, 1902.

Application filed April 19, 1902. Serial No. 103,681. (No model.)

To all whom it may concern:

Be it known that I, CARL G. NYBERG, a citizen of the United States, and a resident of Worcester, in the county of Worcester and State of Massachusetts, have invented certain new and useful Improvements in Pumps, of which the following is a specification.

This invention relates to improvements in pumps for the purpose of removing obstructions in water-pipes—such as, for instance, sink-pipes, water-closet or washbowl pipes, bath-tub discharge-pipes, and drain or sewer pipes, &c.—and for such purpose I make use of a pump having a movable piston 15 provided with a reversible valve-seat and a valve therein and a reversible valve-seat in the lower end of said pump having also a valve therein, the device being so constructed as to permit the said valve-seats and their 20 valves to be reversed in changing the pump from a force to a lift pump, and vice versa, for the purpose of removing obstructions in water, sewer, or drain pipes, as above described. This is very essential, as it has been 25 found that certain obstructions or accumulations in pipes will sometimes yield and be caused to be dislodged more readily by pressure than by suction, and vice versa. If such obstructions cannot be dislodged by pressure, 30 they may be dislodged by suction, and this can only be ascertained by trial first with one kind of pump and then by another kind, which would require the use of two kinds of pumps—namely, a lift and a force pump. I 35 simplify this operation by the use of a single pump, which can be changed from a force-pump to a lift-pump, as occasions may require, simply by reversing the positions of the valve-seats and their valves, as will be hereinafter 40 more fully described, reference being had to the accompanying drawings, wherein—

Figure 1 is a top plan view of the invention. Fig. 2 is a longitudinal section on the line 2 2 in Fig. 1, showing the valves in position when using the device as a suction or lift pump. Fig. 3 is a similar longitudinal section showing the valves in position when using the device as a force-pump and showing its lower end temporarily connected by a 45 flexible fitting to the soil discharge-pipe of a water-closet bowl, and Fig. 4 is a detail bot-

tom plan view of such flexible water-closet-bowl fitting.

Similar letters refer to similar parts wherever they occur on the different parts of the 55 drawings.

In the drawings, A represents a pump-cylinder of any suitable size provided with a closed bottom B and an external lower flange C, as shown in Figs. 1, 2, and 3.

To the under side of the flange C is secured 60 a rubber packing-ring D for the purpose of establishing an air and water tight connection between the lower end of the pump and the sink, washbowl, bath-tub, &c., from the 65 discharge-pipes of which obstructions are to be removed.

E is the centrally-perforated cap at the upper end of the pump-cylinder, as usual.

F is the piston-rod, to the lower end of which 70 is secured in a suitable manner the centrally-perforated piston G, which may be moved longitudinally in the cylinder A by taking hold on the piston-rod handle H, or, if so desired, the said piston may be operated by a 75 lever or other well-known pump-actuating device, as may be most practical or convenient.

g in Figs. 2 and 3 is a leather or other suitable piston-packing on the piston G, as is common in devices of this kind.

The central perforation in the piston G is 80 interiorly screw-threaded for the reception of an exteriorly-screw-threaded tubular valve-seat sleeve I, in which is guided the valve-stem k of the valve K, as shown in Figs. 2 and 3.

k' k' are stop projections at the end of the valve-stem to prevent the valve from moving out of the valve-sleeve I during the operation 85 of the pump.

In the bottom B of the pump-cylinder is a central screw-threaded perforation for the reception of an exteriorly-screw-threaded tubular valve-seat sleeve L, in which is guided the valve-stem m of the valve M, as shown in Figs. 2 and 3.

m' m' are stop projections at the end of the valve-stem to prevent the valve from moving out of the valve-sleeve L during the operation 90 of the pump.

When it is desired to use the pump as a lift-

pump, the valve-sleeves I L and their valves K M are arranged in the positions shown in Fig. 2. When it is desired to use the pump as a force-pump, the positions of the valve-sleeves and valves are reversed, as shown in Fig. 3, and this is accomplished simply by unscrewing said valve-sleeves and placing them in a reversed position, as shown, respectively, in said Figs. 2 and 3.

- 10 In Fig. 2 N represents a kitchen-sink provided, as usual, with a discharge-cup N' and discharge-pipe N", as is common in sinks.

To the lower end of the pump-cylinder A is connected a valve or cut-off O, provided with 15 a stop-cock O', as shown in Figs. 1 and 2. P in said figures represents a flexible pipe connected to said cut-off and adapted to be connected to any suitable source of pressure for the purpose of forcing a supply of water into 20 the lower portion of the pump previous to commencing the pumping operation. After the pump has been filled with water the cock O' is closed before commencing the pumping operation. Where water under pressure is 25 not readily obtainable, the pump may be filled by removing the cover E and water poured in at the upper end of the pump-cylinder A.

In practice I prefer to provide the upper end of the pump-cylinder A with a delivery-spout A', to which may be attached a flexible pipe A", so as to discharge the matter pumped up from the sink-pipe, &c., into a bucket or other suitable receptacle, as may be most convenient.

- 30 In using the pump on a sink or other similar device the pump may be temporarily secured in position by means of clamps Q Q and screws q q, as shown in Figs. 1 and 2.

In Fig. 3 S represents the lower open end of a water-closet bowl, and if it is desired to clean the soil-pipe connected to said bowl I make use of a preferably tapering flexible metal tube or fitting T, which in practice I provide with an exterior rubber or leather lining t, as shown in Figs. 3 and 4. Such fitting may be secured in a suitable manner to the lower end of the pump when in use. The lower end of such fitting is adapted to be inserted in the lower portion of the water-closet bowl, and, being flexible, it will conform to the shape of the lower end of such water-closet bowl, so as to make a close and air-tight connection between the fitting and bowl when using the device for removing obstructions in the water-closet-bowl soil-pipe.

In using the device for the removal of obstructions in discharge-pipes from sinks, washbowls, water-closet bowls, &c., the lower end of the pump is held or secured air-tight in position to such sinks or bowls in a manner as above described. The device can then be used as a lift-pump, as shown in Fig. 2, or

if such operation should fail to dislodge the obstructions the pump can readily be changed into a force-pump simply by changing the 65 positions of the valve-sleeves I L and their respective valves K M, as represented in Fig. 3, and it will thus be seen that the pump can readily be changed from a lift to a force pump, or vice versa, as circumstances may 70 require.

Throughout the description I have employed the terms "lift-pump" and "force-pump" to make it plain that at one time the pump may operate by suction to raise or withdraw the obstruction from the waste-pipe or 75 may be used as a plunger or pressure-pump to force the obstruction down and out of the waste-pipe into the sewer. The two terms, therefore, are used in a relative sense only 80 and not as being descriptive of any particular construction of pump.

What I wish to secure by Letters Patent and claim is—

1. A convertible pump comprising a pump-barrel provided at its bottom with means for connecting said barrel air-tight with a waste-pipe, a reciprocating piston arranged in the barrel, reversible valve-seats fitted in the bottom of the barrel and in the piston, and valves 85 loosely fitted in said seats, substantially as and for the purpose specified.

2. A convertible pump, comprising a pump-barrel provided at its bottom with means for connecting said barrel air-tight with a waste-pipe, a reciprocating piston arranged in the barrel, tubular threaded valve-seats reversibly fitted in the piston and the bottom of the barrel, and valve-stems loosely fitted in said seats, each of said stems being provided on 95 one side of the seat with a valve adapted to close against said seat, and at its opposite end with projections arranged to engage the other side of the seat and limit the opening movement of the valve, substantially as and 100 for the purpose specified.

3. A convertible pump, comprising a pump-barrel provided at its bottom with means for connecting said barrel air-tight with a waste-pipe, a reciprocating piston arranged in the 110 barrel, reversible valve-seats fitted in the bottom of the barrel and in the piston, valves loosely fitted in said seats, a discharge-spout connected with the upper end of the barrel, and a valved water-pipe connected with the lower end of said barrel, substantially as and for the purpose specified.

In testimony whereof I have affixed my signature in presence of two witnesses.

CARL G. NYBERG.
